CLAIM

The ornamental design for an umbrella as shown and described.

DESCRIPTION

FIG. 1 is a rear and bottom perspective view of an umbrella, showing my new design;

FIG. 2 is a front view thereof;

FIG. 3 is a rear view thereof;

FIG. 4 is a left side elevation view thereof;

FIG. 5 is a right side elevation view thereof;

FIG. 6 is a bottom plan view thereof; and,

FIG. 7 is an enlarged view of portion 7 shown in FIG. 1. The dash-dash broken lines in the drawings represent portions of the umbrella that form no part of the claimed design. The dot-dash broken lines in the drawings denote the boundaries of the enlarged detail view and form no part of the claimed design.
